AUTOMATIC MAGNETIC TACK HAMMER

Harry G. Anderson, Alameda, Calif.

Application February 20, 1950, Serial No. 145,271

4 Claims. (Cl. 1—45)

1

This invention relates to tack hammers and more particularly to an automatic tack hammer of the magnetic type.

Among the objects of the invention are the following: To provide a tack hammer embodying a gravity type feed means adapted to transfer tacks or small nails one by one from a suitable storage chamber to a location adjacent the face of the head of the hammer, and magnetic means residing within the hammer head, adapted by magnetic attraction alone to swing the gravity-urged tack out of its path of movement and into fixed relation on the face of the hammer head, in which position the tack may be driven into a suitable object; to provide a tack hammer of the aforesaid type in which the tacks are transferred one by one from the storage chamber to the magnetized face of the hammer head solely by the natural forces of gravitation and magnetism; to provide a tack hammer head embodying a magnet so arranged within the head as to allow tacks to gravitate freely down a suitable guide channel at the side of the head until the tacks approach the hammering surface or face of the head, at which point said magnet is effective to retain the head of the tack against the hammering surface and prevent further gravitational movement of said tack; and to provide an efficiently operable and comparatively simple tack hammer of the magnetic type.

In summary, the tack hammer of the invention comprises a hammer head, a handle having a suitable storage chamber for tacks, guide means in the form of a tack-head channel extending from a tack outlet passage for the storage chamber along the side of the hammer head and terminating in a curved tack delivery portion at the hammering surface of the hammer head, feed control means in association with the guide channel and adapted to admit the tacks one by one to the end or curved portion of the guide channel, and a magnet within the hammer head and so arranged therein as to not impede the gravitational movement of the tacks along the guide channel, and further adapted to cause a tack issuing from the terminus of the guide channel to be arrested and maintained at the hammering surface. As will hereinafter more clearly appear, the magnet-bearing portion of the hammer head may be made yieldingly movable with respect to the balance of the hammer, said movement taking place when the hammer is struck against the object to receive a tack, and the movement of said magnet-bearing portion may be utilized to actuate the tack feed control mechanism to feed the tacks one by one to

2

the hammering surface, each yielding movement of the magnet-bearing portion being effective to feed a single tack to said surface. Alternately, the hammer head may be so constructed as to embody no relatively movable parts, and a manually operable feed control system may be utilized to feed the tacks one by one to the hammering surface of the head. Suitable lever control means may be embodied in the movable head modification of the hammer to prevent movement of the head portion, thereby preventing further sequential tack feed and enabling the use of the magnetized hammer head end to fully drive a tack within the object in which it has been initially positioned.

Other objects and advantages of the invention will be apparent from the following description taken in conjunction with the drawings forming part of this specification, and in

20 which:

Figure 1 is a view in side elevation of a tack hammer embodying the invention, with portions of the handle and head being shown in section;

Figure 2 is a partial view in bottom elevation of the hammer;

Figure 3 is a view taken along lines 3—3 of Figure 1;

Figure 4 is a partial view of the hammer head corresponding to the showing of the hammer head in Figure 3, but illustrating the magnet-bearing portion of the head in its inward or retracted position;

Figure 5 is an enlarged view in section taken along lines 5—5 of Figure 1;

Figure 6 is a view in section taken along lines 6—6 of Figure 4;

Figure 7 is a view partly in elevation and partly in section, showing a modified form of the tack hammer of the invention;

Figure 8 is a left side elevational view of the hammer of Figure 7;

Figure 9 is a view in section taken along lines 9—9 of Figure 7; and

Figure 10 is a detailed view taken along lines 10—10 of Figure 7.

45 Referring to the drawings for further details of the invention, the tack hammer, shown in Figures 1—6, comprises a hollow handle 10 having an enlarged portion 12 defining a relatively large tack storage chamber 14, said handle being provided at its lower end with a cap 16 adapted to be removed in order to charge the handle with tacks, and said handle is secured at its other end, as by screws 18, to a plug 20, shown as being integral with the hammer head 22. The plug 20 is provided with an extension portion 24 having

a flat surface 26 constituting a storage shelf for tacks within the chamber 14, and said portion 24 is provided with a rounded longitudinally arranged chamber 28, the lower side of which is in open communication with a slot 30 in the outer side of the extension portion 24. The plug 20 is also provided with a forwardly extending portion 32 having a curved extension 34 of the slot 30. Curved strip plates 36 secured to the core portion 32, as by screws 38, restrict the mouth of the slot 34 so that tacks, the heads of which may reside in the slot 34, will be held in place within the slot for guided movement, as will be hereinafter more clearly described. The handle 10 is provided with a slot 40 having a width equal to the distance between the guide plates 36, and thus tacks within the slot 40 are held therein for guided movement.

The hammer head 22 is comprised of a fixed portion 42 integral with the core 20 and a movable portion 44 terminating in the hammering surface 46. The portion 44 of the hammer head is threadably engaged at 48 with the reduced diametral portion 50 of a cylindrical connector member 52 residing within the largest diametral bore 54 of hammer head portion 42, said member 52 being provided with reduced diametral portions 56 and 58 fitting within, respectively, reduced diametral bore portions 60 and 62 of the head portion 42. A spring 64 within bore portion 60 and in engagement with the reduced diametral extension 56 of member 52 serves to urge the movable portion of the hammer head outwardly with respect to the fixed portion 42. A pair of screws 66 extending through slots 68 in head portion 42 and into threaded engagement with the member 52 serve, in conjunction with the lower ends of the slots 68, to prevent movement of the head portion 44 outwardly beyond the position shown in Figure 1.

In the head portion of the tack hammer, the guide means for tack feed comprise the slot 70 in head portion 42, which slot is in alignment with slot 34, with the mouth portion 72 of said slot having a width corresponding to the space between the strip plates 36. The movable head portion 44 of the hammer is provided with a slot 74, the mouth of which is restricted by cover plates 76 secured to the head portion 44 by screws 78. The slot 74 is provided with a curved terminus 80 merging into the hammering surface 46. When the movable head portion 44 is in its outward position, as shown in Figures 1 and 3, guide pins 82, carried by head portion 42 and slidably within guide bores 84 in cover plates 76, serve to maintain the tacks in the guideway during their passage between the two-head portions of the hammer, and the pins 82 serve the further function of preventing any relative rotational movement between the head portion 44 and the connector member 52 threadably engaged therewith.

The guide or feed channel comprising aligned slots 34, 70 and 74 is provided with a trigger type feed control mechanism adapted to admit the tacks one by one to the lower portion of said channel. This feed mechanism is comprised of a pair of plates 86 and 88 seated in channels provided in hammer head portion 42. The plates 86 and 88 are provided, respectively, with cam slots 90 and 92 through which the screws 66 extend, and they are further provided, respectively, with fingers 94 and 96 integral therewith. Plates 98, secured to the hammer head portion 42 by screws 100, are provided with open ended slots

102 serving as guideways for the screws 66 as the hammer head portion 44 is moved relative to the head portion 42.

The head portion 44 and the connector member 52 are provided with aligned bores which together constitute a chamber 104 for a cylindrical magnet 106, preferably of "Alnico." The offset relation of the magnet with respect to the median line of head portion 44 and connector member 52, as clearly shown in Figure 5, serves to inhibit the magnetizing of the guide channel region of the hammer head portions 42 and 44, thus allowing free gravitational movement of the tacks along this guide channel in a manner to be hereinafter more clearly described.

The operation of the magnetic tack hammer is as follows. As a result of manipulation of the hammer manually by the conventional arm movements, it will be understood that tacks will be fed off of the shelf 26 to collect in the region of the mouth of channel 28. The tacks will gravitate into the channel 28 and become so oriented that the stems thereof will pass through the slot 40 in the handle, with the head portions of the tacks residing within slot 30. After becoming so oriented, the tacks will move in succession along the slot 34 until the first one comes in contact with the finger 94 of trigger plate 86, as shown in Figure 3, and when this occurs there will generally be an unbroken line of tacks in head-to-head relation from the lowermost one designated as 124 in Figures 3 and 4, in contact with finger 94 up to the region of channel 28. When the operator desires to insert a tack in an appropriate object, he strikes the hammering surface 46 against the object to force the movable head portion of the hammer inwardly against the action of spring 64, and this inward movement of the movable head portion causes the screws 66 to be moved upwardly to cam trigger plate 86 outwardly and plate 88 inwardly, thereby freeing the tack that was in engagement with finger 94 and allowing it to move along the guide channel 70 into engagement with finger 96 (Fig. 4). As the hammer stroke is completed and the hammer is moved away from the surface of the object, the movable head portion of the hammer is urged outwardly by the action of spring 84 to its normal position, thereby causing trigger plates 86 and 88 to be moved into the position shown in Figure 3. The movement of plate 86 into this position arrests the next tack in the feed row, and the movement of plate 88 into this position frees the tack that was in engagement with finger 96 so that said tack gravitates downwardly through guide channel 74 and the curved end thereof. As the tack reaches the end of the curved portion 80 of the guide channel its gravitational movement is overcome by the magnet 106, with the result that the tack comes to rest with its head portion in alignment with the magnet. A subsequent blow of the hammer will position the tack in the object, and at the end of this second hammer blow the return of the movable head portion of the hammer to its normal position will result in the feed of another tack to the hammering surface 46. After the first or tack feed conditioning blow of the hammer, it will be understood that each succeeding hammer blow will serve to position a tack in the object to which it is to be affixed and to replace said tack with another one on the hammering surface 46. The hammer may then be turned around to utilize the end of head portion 42 as the driving mem-

ber to complete the driving of the tacks which were affixedly positioned in the object.

I have also provided means whereby the surface 46 may be utilized as the driving or anvil surface to accomplish the complete driving of the tacks within the object, which means are operatively effective to prevent the feeding of tacks to the surface 46 when the same is being utilized for this tack driving purpose. Such means comprise a cable 112 extending through the passageway 114 in the hammer head portion 42 and secured at one end to an ear 116 carried by the portion 58 of connector member 52. The other end of the cable is fastened to a crank lever 118 pivotally attached at 120 to the handle 10 and provided with a hand grip extension 122. It will be clear that when the operator moves the extension 122 of the lever 118 toward the handle 10 the movable head portion 44 of the hammer will be moved to the position shown in Figure 4, in which position the head portion 44 is in abutting relation with the head portion 42 and the finger 96 is in blocking relation to the feed channel. The surface 46 may then be used as the anvil surface for the driving of the tacks, and during this phase of use of the hammer further tack feed is prevented.

In the course of the normal swinging action of the hammer, particularly when the hammer is moved upward preparatory to a further downward or hammering stroke, there will be a tendency for the tacks within slots 34 and 70 to slide or move backwardly toward the storage chamber 14. In order to inhibit this action and to preserve the continuity of the feed row of tacks within slots 34 and 70, I have provided an abutment member in the form of a shoulder 125 in the handle 10 near the outlet of slot 30, said shoulder being effective to block backward movement of the tacks, while not affecting the forward feed of the same.

In Figures 7-9 there is shown a modified form of the automatic magnetic tack hammer of the invention. This modification of the hammer differs from the modification shown in Figures 1-6 in that it may be considered to be of the linear type, rather than the T-shaped or cross-head type, and, also, in that the tack feed control means is manually operable rather than being automatically operable by relative movement between portions of the hammer head. The modified form of the hammer comprises a head 210 provided with a hammering surface 212, a guide channel 214 having the curved terminus 216, a chamber for the reception of the magnet 218, and a boss 222 carrying a threaded plug 224 serving as a closure for the magnet chamber. Suitably secured to the boss 222, as by screws 226, is a cylindrical tube 228 serving as the storage chamber for the tack supply. The tube 228 is provided with a removable closure cap 230 for tack loading purposes. A tack feed tube 232, provided with a tack slot 234 is suitably secured, as by welding, to a connector member 236, with the latter in turn being suitably secured to the tube 228 by welding or otherwise. Aligned apertures in the members 228, 236, and 232 constitute the feed passageway providing for communication between the interior of the tube 228 and the interior of the tube 232. Inversion of the hammer, coupled with a slight agitation of the same will serve to feed a supply of tacks through the passageway 238 into the feed chamber of tube 232. When the hammer is oriented with the head portion 210 directed downwardly, the

tacks gravitate into engagement with plug member 240 which defines with the slotted wall of tube 232 the feed channel 242 which is in alignment with the hammer head channel 216. The plug member 240 may be suitably secured, as by welding or the like, to the interior of tube 232 and may be provided with an additional connection in the form of a dowel 244 with head 210. The shoulder 246 in slot 234 serves to prevent the backward movement of tacks into the feed chamber of tube 232 after they have once passed into the channel 242.

In order to shield the operator's hand from the points of the tacks protruding through the slot 234 and to give the handle portion of the hammer an exterior form comfortably fitted to the operator's hand, I have provided the shield or skirt member 246 in secured relation, as by one or more screws 248, to the connector member 236. The shield 246 laterally envelops the tube 232, as best shown in Figure 9.

This modified form of the tack hammer of the invention is also provided with means for feeding the tacks one by one to the hammering surface 212. The feed means comprise a semi-sleeve member 250 rotatably mounted on the feed tube 232 and provided at its lower end with a ring portion 252 embracing the circumference of the tube 232. The ring portion 252 is provided with an angularly inclined slot 254 defining oppositely disposed and vertically offset pawls 256 and 258. When the semi-sleeve 250 is in its normal position, as shown in Figure 10, the pawl 256 is in blocking relation to the tack feed channel 242. A slight rotation of the semi-sleeve 250 to the right, as viewed in Figure 10, will bring the slot 254 into communication with the feed channel 242, thereby admitting a single tack to the slot 254. A subsequent reverse rotation of the semi-sleeve 250 is effective to bring the outlet end of slot 254 into communication with channel 216 of head 210 to thereby allow the tack within slot 254 to pass into the channel 216 and gravitate downwardly until it reaches the field of attraction of the magnet 218 at the hammering surface 212. This reverse rotation of the semi-sleeve 250 brings the pawl 256 into blocking relation with respect to the feed channel 242. Thus, by rotating the semi-sleeve 250 first in one direction and then in the other, the tacks will be fed one by one to the hammering surface 212.

Manually operable rotating means are provided for the semi-sleeve 250, said means comprising a semi-ring gear 260, carried by the semi-sleeve 250, in mesh with the gear-tooth segment 262 of ring 264. A shoulder 266 of tube 228 together with the lower end of connector member 236 serve as the positioning and bearing means for ring 264. When the hammer is grasped so that the operator's hand is located on the tube 228 and the protector skirt 246 below the bearing ring 266, and with the butt of the hand disposed toward the hammer head, it will be clear that the thumb or forefinger, or both, may be readily utilized to manipulate the control ring 264 in order to feed the tacks one by one to the hammer head in the manner above described.

While specific embodiments of the tack hammer of the invention have been illustrated and described, it is to be understood that the hammer is subject to modification within the spirit of the invention and the scope of the appended claims.

What I claim as new and desire to secure by Letters Patent is:

1. A tack hammer comprising a handle having

a. tack storage chamber, a hammer head carried by said handle and having an end surface to which tacks are to be fed, a tack feed channel extending from said storage chamber to said end surface comprising an intermediate channel portion at the side of said head through which the tacks are moved by gravity and an arcuate end portion terminating at said end surface adapted to direct said gravity-fed tacks toward said end surface, tack feed control means for said hammer comprising means reciprocally movable transversely to said feed channel and operable to admit tacks one by one to the arcuate end portion of said channel, and a magnet within said head laterally shielded so as to limit its tack-restraining magnetic effect to said end surface, said magnet being operable to overcome the kinetic energy of gravitational movement of a tack issuing from the arcuate end portion of said channel and hold said tack at said end surface.

2. A tack hammer comprising a handle having a tack storage chamber, a hammer head comprising a fixed portion secured to said handle and a movable portion carried by said fixed portion for limited axially reciprocal movement with respect thereto, said movable portion of the head having an end surface to which tacks are to be fed, a tack feed channel extending from said storage chamber along the side of said head portions and having an arcuate end portion terminating at said end surface, said feed channel being adapted under the action of gravity and the manual manipulation of said hammer in conventional manner to feed tacks from said chamber to said end surface, yieldable means urging said movable head portion outwardly with respect to said fixed head portion, tack feed control means for said hammer comprising gate means carried by said fixed head portion for reciprocal movement transversely of said channel and means carried by said movable head portion in camming engagement with said gate means and operable upon reciprocal movement of said movable head portion to impart a reciprocal movement to said gate means and thereby pass a tack through said gate means for gravitational movement to the end surface of said movable head portion, and a magnet within said movable head portion laterally shielded so as to limit its tack-restraining effect to said end surface, said magnet being operable to overcome the kinetic energy of gravitational movement of a tack issuing from the arcuate end portion of said channel and hold said tack at said end surface.

3. The tack hammer set forth in claim 2 provided with means to render said tack feed control means inoperative to feed tacks to said end surface upon the striking of said end surface against an object, said means comprising a crank lever carried by said handle and a cable secured at one end to said lever and having its other end secured to said movable head portion, said lever and cable being operable upon the forced pivoting of said lever to fixedly position said movable head portion with respect to said fixed head portion.
4. A tack hammer comprising a hammer head having an end surface to which tacks are to be fed, a hollow tubular member secured in fixed relation to said head and forming a guideway for tacks, a tack guide channel in one side of said head having an arcuate end portion terminating at said end surface of said head, an elongated guide slot in said tubular member in alignment with said guide channel, said slot and guide channel forming the passageway means for the gravitational movement of tacks from said tubular member to the end surface of said head, a member sleeved on said tubular member having a slot therethrough angularly directed with respect to the guide slot of said tubular member and in overlying relation to a portion of said guide slot, means for rotating said member a sufficient amount in each direction of rotation to first bring the upper end of the slot of said member into coincidence with said guide slot and then the lower end of said slot into coincidence with said guide slot to thereby feed tacks one by one to the guide channel of said head, and a magnet within said head laterally shielded so as to limit its tack-restraining magnetic effect to said end surface, said magnet being operable to overcome the kinetic energy of gravitational movement of a tack issuing from the arcuate end portion of said channel and hold said tack at said end surface.
